ADAPTER FOR FEEDING PARALLEL STACKED TRANSPARENCIES TO A SLIDE PROJECTOR OR SIMILAR ARTICLE

David E. Hansen, Rochester, N.Y., assignor to Eastman Kodak Company, Rochester, N.Y., a corporation of New Jersey

Filed Jan. 23, 1967, Ser. No. 5,511

Term of patent 14 years

(Cl. D61—1)

FIG. 1

FIG. 2

FIG. 3

FIG. 4

FIG. 5

FIG. 6

FIG. 7

FIG. 1 is a front perspective view of an adapter for feeding parallel stacked transparencies to a slide projector or similar article showing my new design;

FIG. 2 is a left side elevational view;

FIG. 3 is a right side elevational view thereof;

FIG. 4 is a top plan view thereof;

FIG. 5 is a front elevational view thereof;

FIG. 6 is a bottom plan view thereof; and

FIG. 7 is a rear elevational view thereof.

The slide projector and transparencies shown in dotted lines in FIG. 1 is for illustrative purposes only.

I claim:

The ornamental design for an adapter for feeding parallel stacked transparencies to a slide projector or similar article, as shown and described.
